SAFETY PILOT FOR GAS BURNERS

George A. Peterson, Sydney, New South Wales,
Australia

Application October 12, 1946, Serial No. 702,957

10 Claims. (Cl. 158—117.1)

1

This invention relates to a safety pilot for gas burners, and is directed to an improved solution of the problems of maintaining an adequate pilot flame without waste of fuel and of preventing supply of fuel to the main burner unless the pilot is in proper operation.

While arrangements to shut off the supply of gas to a burner when its pilot flame is extinguished have been known, the principles of this invention make possible a device for this purpose which is simpler and more positive in action than those previously employed. In addition, the invention makes it possible to counteract influences, such as fluctuations in gas main pressure and drafts of air striking the flame, which may cause extinction of the pilot.

The objects of the invention include the following:

To increase the safety and reliability of gas-burning apparatus;

To minimize the possibility of failure of a pilot flame, while at the same time economizing on fuel;

To provide a shut-off control of gas supplied to the main burner responsive to the condition of the pilot flame which is sensitive and quick in operation;

To maintain a constant pilot flame, notwithstanding extraneous disturbances; and

To accomplish the above-named objectives by means which are simple, rugged, accurate and positive in action, and economical to manufacture.

Other objects and advantages of the invention, more or less ancillary to those stated above, will be apparent to those skilled in the art from the description herein of the preferred embodiment of the invention.

Referring to the drawings:

Fig. 1 is a plan view of a gas burner, pilot, and control devices in accordance with the invention;

Fig. 2 is a partial vertical section, taken on the plane indicated by the line 2—2 in Fig. 1; and

Fig. 3 is an end elevation of the temperature-responsive device and pilot burner.

The invention is employed in connection with a main gas burner 11, which may be of any form and be applied to any heating function. The burner 11 is supplied through a line 12, a safety valve 13, and a line 14. If desired, a thermostat valve 16 may be incorporated in the line 12, and an external manual control valve (not shown) may be provided.

The pilot burner 17 consists of a section of tubing having a reduced end 18 from which the

2

main pilot flame 19 is projected to the burner 11. The pilot is supplied from a line 21 through a control valve 22 and a line 23. The valve 22 is operated to throttle the supply of gas to the flame and automatically maintain the desired strength of flame. The valve is by-passed by a connection 24 between the lines 21 and 23, the by-pass incorporating a reduced section of tubing or other restriction graduated to pass the minimum amount of gas sufficient to maintain the pilot flame.

The temperature-responsive portion of the device comprises a sleeve 26 threaded into a fixed frame member 27, and having a crosspiece 28 fixed on its free end. Rods 29 fixed in the ends of the crosspiece 28 and a yoke 31 constitute, with the crosspiece and yoke, a rectangular frame. An expansion rod 32 fixed centrally in the yoke 31 extends between the rods 29 and through the sleeve 26, being free to move longitudinally in the sleeve. The rods 29 and 32 may be hollow if desired.

The control is exerted through the differential thermal expansion of the rod 32 with respect to the rods 29. To this end, the pilot burner is disposed parallel to and underneath the exposed portion of the rod 32, and is provided with a plurality of small orifices 33 along its length. The flames from the orifices 33 heat the rod 32, but do not heat the rods 29 to any considerable extent because of their lateral displacement. Heat supplied from other sources, as the furnace walls or the main burner, will affect all the rods substantially equally, and cause no differential expansion. The rods 29 and 32 and the sleeve 26 are formed of the same material, heat-resisting steel, such as 18-8 stainless steel, being found satisfactory. Any convenient method of fixing these parts in the cross member 27 and 31 may be employed.

Operation of the valves 13 and 22 is accomplished through a cross bar 34 fixed on the outer end of the rod 32 and thus moved toward or away from the frame member 27 by the differential expansion of the rods. The pilot control valve 22 is normally open, but as the rod 32 expands, its poppet 36, which is controlled by the bar 34, moves toward the seat 37, throttling the pilot flame and maintaining it at the desired intensity. A compression spring 38, tending to close the valve, keeps the stem of the poppet 36 in contact with an adjusting screw 36a threaded into the bar 34 unless prevented from doing so by the seat 37.

55 The safety valve 13 is held closed when the

apparatus is cold by a tension spring 39, attached in any convenient manner to the poppet 41 of the valve and the fixed member 21. The stem 42 of the valve slides in a bore 43 in the bar 34, and is fitted with a nut 44 adjustable on the stem. The nut is set for a lost motion connection such that the spring 39 holds the valve 13 closed until the rod 32 has expanded approximately sixty per cent of the amount which corresponds to normal operation of the pilot.

In practice, the maximum rate of supply to the pilot flame should be at least twice the operating rate, and the arrangement of the two valves should be such that the safety valve 13 opens enough to permit ignition of the main burner before the pilot burner valve 22 closes enough to affect the pilot flame substantially. Overrun of the valve 13 is prevented by throttling of the pilot by the valve 22.

By virtue of the lost motion connection between the rod 32 and the valve 13, if the pilot should become extinguished, the valve 13 will rapidly close. The rod 32, being substantially hotter than the rods 29, will cool much more rapidly.

The heat loss by radiation is approximately proportional to the fourth power of the absolute temperature. The temperature difference of the rods, and thus their length difference, will thus vary with time, when the pilot is extinguished, according to an exponential curve which drops very steeply at first. As soon as the differential contraction amounts to about forty per cent, which will be in a small fraction of the total cooling time, the valve 13 will close and shut off the main burner. In practice, the apparatus may be designed to operate with about 500 degrees Fahrenheit temperature difference between the rods 32 and 29.

Since the operation depends upon the linear expansion of the rods, and the force is applied directly to the valves in a direction parallel to the axis of the rods, the control apparatus will be exceptionally positive and accurate in operation.

It should be noted that the specific form of the valves, except insofar as involves suitability for practical operation in the combination disclosed herein, is immaterial, and the illustration of the valves herein may be regarded as schematic. The poppet type of valve is regarded as most suitable, however. The dimensions of the valves will of course be readily determinable in terms of the fuel requirements of the burners, the length and thermal expansion coefficient of the rods 29 and the exposed portion of the rod 32, and the preferred operating temperature differential between the rods 32 and 29.

It will be obvious to those skilled in the art that a remote electrically-operated valve may be substituted for the direct-operated valve 13 by installing a switch of a well-known type operated by a small movement of its actuator in position to be operated by the rod 32 or bar 34. With this construction, substantially instantaneous opening and closing of the main burner valve will result.

The operation of the control device to regulate the pilot flame through the differential expansion of the rods and the action of the valve 22 will be apparent from the foregoing description. If a draft should affect the pilot flame, the effect of the flame on the central rod 32 will be decreased, causing contraction of the rod and greater opening of the valve 22.

An optional feature of the invention is the

provision of a shield 47 of sheet metal or the like surrounding the pilot burner 17 and the exposed portion of the rod 32. Such a shield, which should be provided with openings at top and bottom for circulation of air, will tend to confine the heat from the pilot burner to the rod 32 and shield the rods 29 from the burner.

The specific description herein of the preferred mode of employment of the invention should not be regarded as restrictive, since the scope of the invention is to be determined from the appended claims.

I claim:

1. In a heating device, a main burner, a pilot burner therefor, a normally closed valve for supplying the main burner, a normally open valve for supplying the pilot burner, a thermally responsive control device exposed to the heat of the pilot burner, a member moved by the control device, lost motion coupling means connecting the main burner valve to the member so that the valve will be opened after a predetermined movement of the member, and means connecting the pilot burner valve to the member so that the valve will be operated toward its closed position by movement of the member, the pilot burner valve being adapted to regulate the pilot burner to maintain a normal pilot flame and thus hold the main burner valve open, the control device being connected to close the main burner valve upon its initial cooling in the event of extinction of the pilot flame.

2. In a heating device, a main burner, a pilot burner therefor, a normally closed valve for supplying the main burner, a normally open valve for supplying the pilot burner, a linearly expansible member exposed to heat from the pilot burner, a linearly expansible member relatively unexposed to heat from the pilot burner, a member moved by the differential linear thermal expansion of the members, lost motion coupling means connecting the main burner valve to the member so that the valve will be opened after a predetermined movement of the member, and means connecting the pilot burner valve to the member so that the valve will be operated toward its closed position by the said movement of the member.

3. In a heating device, a main burner, a pilot burner therefor, a normally closed valve for supplying the main burner, a normally open valve for supplying the pilot burner, a linearly expansible member exposed to heat from the pilot burner, a linearly expansible member relatively unexposed to heat from the pilot burner, a member moved by the differential linear thermal expansion of the members, lost motion coupling means connecting the main burner valve to the member so that the valve will be opened after a predetermined movement of the member, and means connecting the pilot burner valve to the member so that the valve will be operated toward its closed position by the said movement of the member, the pilot burner valve thus regulating the pilot burner to maintain the main burner valve open as long as the pilot burner is lit.

4. In a heating device, a main burner, a pilot burner therefor, a normally closed valve for supplying the main burner, a normally open valve for supplying the pilot burner, a linearly expansible member exposed to heat from the pilot burner, a linearly expansible member relatively unexposed to heat from the pilot burner, a member moved by the differential thermal

expansion of the members from a cold position to a hot position, lost motion coupling means connecting the main burner valve to the member so that the valve will be opened after a movement of the part at least half way from its cold to its hot position, and will be fully opened when the member is substantially in its hot position, and means connecting the pilot burner to the member so that the valve will be operated toward its closed position by the said movement of the member, the pilot burner valve being adapted to regulate the burner to maintain the member in its hot position.

5. In a heating device, a main burner, a pilot burner therefor, a normally closed valve for supplying the main burner, a normally open valve for supplying the pilot burner, a lost motion coupling control device exposed to the heat of the pilot burner, a member moved by the control device from a cold position to a hot position, means connecting the main burner valve to the member so that the valve will be opened after a movement of the member at least half way from its cold to its hot position, and will be fully opened when the member is substantially in its hot position, and means connecting the pilot burner valve to the member so that the valve will be operated toward its closed position by the said movement of the member, the pilot burner valve being adapted to regulate the burner to maintain the member in its hot position.

6. In combination, a heat responsive device comprising a sleeve fixed at one end, a cross bar fixed on the free end of the sleeve, a rod slidably mounted in the sleeve and extending from the free end thereof, a yoke fixed on the extended end of the rod transversely thereof, and bars disposed parallel to the rod and fixed in the cross bar and yoke, the sleeve, rod, and bars all having substantially equal coefficients of thermal expansion, whereby exposure of the device to a heat source more intimately coupled with the exposed portion of the rod than with the bars will cause differential expansion thereof and attendant reciprocation of the rod within the sleeve, and whereby uniform exposure of the device to heat will be ineffective to reciprocate the rod; a pilot burner comprising a section for igniting a main burner and a section adapted to heat the exposed portion of the rod; a control valve for the pilot burner, and means connecting said bars and the valve for closing the valve in response to said differential expansion of the bars.

7. A pilot burner and control device comprising a pilot burner, a throttling valve therefor, a first thermally expandable bar exposed to heat from the pilot burner, a second thermally expandable bar parallel to the first and less exposed to heat

from the pilot burner than the first bar, the bars having equal coefficients of expansion, and means connecting said bars and the valve for closing the valve in response to differential expansion of the bars produced by heat from said pilot burner.

8. A pilot burner and control device comprising a pilot burner, a throttling valve therefor, a first substantially horizontal thermally expandable bar exposed to heat from the pilot burner, a second thermally expandable bar parallel to and laterally displaced from the first and less exposed to heat from the pilot burner than the first bar, the bars having equal coefficients of expansion, and means connecting said bars and the valve for closing the valve in response to differential expansion of the bars produced by heat from said pilot burner.

9. A pilot burner and control device comprising a pilot burner, a throttling valve therefor, a first thermally expandable bar, a second thermally expandable bar parallel to the first, the bars having equal coefficients of expansion, the pilot burner including a burner underlying the first bar and adapted to heat the first bar more effectively than the second bar, and means connecting said bars and the valve for closing the valve in response to differential expansion of the bars produced by heat from said pilot burner.

10. A pilot burner and control device comprising a pilot burner, a throttling valve therefor, a first thermally expandable bar exposed to heat from the pilot burner, second and third thermally expandable bars parallel to the first bar and symmetrically disposed on opposite sides of the first bar, the second and third bars being less exposed to heat from the pilot burner than the first bar, and the bars having equal coefficients of expansion, and means connecting said bars and the valve for closing the valve in response to differential expansion of the bars produced by heat from said pilot burner.
